UNITED STATES PATENT OFFICE.

WILLIAM D. SOUTHARD, OF NEW YORK, N. Y.

DESIGN FOR A STOVE.

Specification forming part of Design No. 6,831, dated August 26, 1873; application filed June 28, 1873.

To all whom it may concern:

Be it known that I, WILLIAM D. SOUTHARD, of the city, county, and State of New York, have invented a Design for Cylinder-Stove and Urn, of which the following is a specification:

The nature of my design is fully represented in the accompanying illustration, to which reference is made.

A represents the cylinder of the stove, which is made of sheet-iron. B is the base, which is made of cast-iron. C is the hearth, which has a removable box-damper, D. The base has also ornamental sections E, and a fluted section, F, all inclining upward to the cylinder A. G is the door, composed of a semicircular arch, H, with two Gothic mica openings, I. J is the cap-plate, in the form of an ornamental hollow truncated cone. K is the urn, composed of an ornamented base, L, a supporting column, M, surmounted by the ewer or basin N, of hemispherical form, with lines O at an

angle of about forty-five degrees, which intersect, representing basket-work. P is a surrounding ornamental border, supported by two ornamented S-shaped brackets, Q, on opposite sides. R is the rim of the basin, which rises above the border P, and is ornamented and serrated.

What I claim as my invention is—

1. The design for the base of the stove, composed of the rope ornament B, fluted part F, and intermediate portion E, having raised points or projections, as shown.

2. The design for the urn K, having the basket-work ewer, the arabesque brackets, and serrated rim, as shown.

3. The design for a cylinder-stove, including the base B E F, the body A, door G H, and top J, as shown.

WM. D. SOUTHARD.
